HANGER FOR PLAYGROUND SWINGS

John Edward Burke, Fond du Lac, Wis., assignor
to Ethlyn M. Burke, Fond du Lac, Wis.

Application July 8, 1935, Serial No. 30,404

2 Claims. (Cl. 248—324)

This invention relates to improvements in hangers for swings, and has for its object to provide an improved hanger adapted to be clamped to a pipe support.

3 An object of the invention is to provide a composite hanger for swings which will comprise a pair of clamping elements and a cooperating bearing box and oil reservoir in which the swing supporting element mounted in the spaced ball bearing races will be disposed.

10 Another object of the invention is to provide an improved hanger for playground swings, in which the inverted U-shape hanger will be formed with laterally extending trunnions on which are mounted ball bearing races, which rest upon the bottom of the bearing box and run in an oil bath, which is protected at all times from the weather and elements.

20 A further object of the invention is to provide an improved playground swing hanger which will be extremely durable and capable of a long period of service, due to the lack of friction between the moving parts brought about by the use of ball bearing races mounted in an oil bath.

25 A still further object of the invention is to provide an improved ball bearing hanger for playground swings which will be highly efficient in use and quite inexpensive to manufacture.

Other objects will appear as the description 30 proceeds.

In the accompanying drawings which form a part of my application,

Figure 1 is a side elevation partly in section of my improved ball bearing playground swing 35 hanger;

Figure 2 is a sectional view taken on the line 2—2 of Figure 1;

Figure 3 is an end elevation partly in section of my improved swing hanger, and

40 Figure 4 is a perspective view of the pivoted hanger element.

Like characters of reference are used throughout the following specification and the accompanying drawings to designate corresponding 45 parts.

In carrying out my invention, I provide an improved ball bearing hanger for playground swings, which comprises an upper clamping element 1 and a lower clamping element 2, adapted 50 to be clamped about a supporting pipe 3, and to cooperate with a combined bearing box and oil reservoir 4, in which the hanger 5 is adapted to be mounted.

The bearing box and oil reservoir 4 is formed 55 with substantially parallel side walls 6, and with

downwardly tapering end walls 7 which are connected and reinforced by the spaced partitions or walls 8, thereby forming the spaced oil reservoirs 9 for the reception of lubricating oil 10. A slot or opening 11 is cut in the bottom of the box 4 between the partition walls 8 and at the lower portion thereof, through which the hanger 5 is adapted to extend.

5 The hanger 5 comprises an integrally formed inverted U-shape element having spaced side 10 arms 12, a connecting portion 13, and a centrally disposed depending hanger portion which terminates in the closed eye 14, and to which the swing chain (not shown) may be attached. The free or lower ends of the side arms 12 are formed 15 with the enlarged bearing portions 15 and the outwardly or laterally extending trunnions 16, which are adapted to support the ball bearing races 17, which in turn, are adapted to seat on or have bearing on the bottom of the box or oil 20 reservoirs 9. The outer ends of the trunnions will be substantially in contact with the inner walls of the box sides 6, so that there will be no lost motion between the hanger and the box supporting the same. It will be seen that the bearing portions 15 engage the inner sides of the ball bearing races 17, to limit their movement inwardly. A hard fibre gasket 18 will be disposed between the bearing box 4 and the lower clamping element 2, so that the lubricating oil 10 in the 30 reservoirs 9 will be fully protected from the weather. One or more suitable oil holes 19 will be formed through the box 4, for filling the same with oil.

The clamping elements 1 and 2, and the bearing box 4, will be fastened on the supporting pipe 3 by means of the bolts 20, which extend through the several parts, as clearly illustrated in Figure 1 of the drawings.

Many minor changes in detail of construction 40 may be resorted to without departure from the spirit of the invention.

Having thus described my invention what I claim as new and desire to secure by Letters Patent of the United States is:

45 1. Means for attaching a swing to an overhead support comprising a hanger box having a seat to engage the support and a clamping element having a complementary seat for holding the box assembled with the support, said box having 50 spaced partitions formed intermediate the ends thereof to form oil reservoirs with a slot therebetween, and a hanger comprising an inverted U-shape member having enlarged free ends terminating in trunnions extending laterally there- 55

from, said trunnions being provided with anti-friction means adapted to be positioned in said reservoirs, and a depending arm disposed intermediate the sides of said hanger and formed integrally therewith and having a closed eye at its 5 free end extending through said slot and below said hanger box.

2. Means for attaching a swing to an overhead support comprising a hanger box having a seat to engage the support and a clamping element 10 having a complementary seat for holding the box assembled with the support, said box having spaced partitions formed intermediate the ends thereof to form oil reservoirs with a slot there-

between, and a hanger comprising an inverted U-shape member having enlarged free ends terminating in trunnions extending laterally therefrom, said trunnions being provided with shoulders and anti-friction means carried by said 5 trunnions and adapted to be clampingly positioned between said shoulders and the end walls of said box, and a depending arm disposed intermediate the sides of said hanger and formed integrally therewith and having a closed eye at 10 its free end extending through said slot and below said hanger box.

J. E. BURKE.
